LOCKING SYSTEM

Edward D. Dall, Cleveland, Ohio, assignor to
Walter F. Wright, Cleveland, Ohio

Application March 19, 1934, Serial No. 716,306

29 Claims. (Cl. 70—264)

This invention relates as indicated to a locking system and pertains more particularly to a system for coincidentally locking a plurality of doors associated with enclosures such as vehicle bodies and the like. While the ensuing description of my invention will refer to the application thereof to a vehicle body having four doors arranged in pairs on opposite sides thereof, it is, nevertheless, to be understood that the principles 5 of my invention are applicable to coincidentally lock or otherwise secure other doors and like openings which may occur in a vehicle body such as doors leading to luggage compartments, etc.

More specifically, my invention relates to the 10 provision of a coincidental locking system for a plurality of doors, in which the actuation of the devices associated with the several doors accomplishes a locking or unlocking of the same, employing a train of mechanical elements whereby 15 the coincidental locking at a plurality of stations may be accomplished mechanically from a single station.

More specifically, my invention relates to the 20 provision of mechanical means for the accomplishment of the foregoing results characterized by simplicity of construction and consequent low cost of manufacture.

It is the principal object of my invention to 25 provide a coincidental locking system of the character described in which the locking of the several doors is accomplished by means effective to disconnect from the several bolts respectively associated with the several doors to be locked, the handles which are normally employed to 30 actuate such bolts in order that the doors may be opened.

It is a further object of my invention to 35 provide a coincidental locking system which is effective, even though force may be applied to the handles associated with the several doors when in the locked position. The bolts on such doors will then be retained in engagement with the stile or jamb adjacent the edge of the door.

It is a further object of my invention to 40 provide a coincidental locking system which is effective upon actuation to positively arrest the latch bolts on a plurality of doors so that they may not be opened from either side and wherein the undogging of the latch bolts on the several doors in order to open the same may be accomplished only at the central station from 45 which the same have been dogged.

Other objects of my invention will appear as 50 the description proceeds.

To the accomplishment of the foregoing and

related ends, said invention, then consists of the means hereinafter fully described and particularly pointed out in the claims; the annexed drawings and the following description setting forth in detail certain mechanism embodying 5 the invention, such disclosed means constituting, however, but one of various mechanical forms in which the principle of the invention may be used.

In said annexed drawings:

Fig. 1 is a fragmentary side elevational view of 10 a portion of a vehicle body showing in diagrammatic outline two adjacent doors with their associated locking mechanism, one of which may, for convenience, be referred to as the master lock; Fig. 2 is a view similar to Fig. 1 showing two other doors on a vehicle similar to that illustrated in Fig. 1 but in Fig. 2 the locks associated with both doors are adapted to be actuated by means located at a remote station such as the master door referred to in Fig. 1; Fig. 3 is a side elevational view of the so-called master lock previously shown in conjunction with the righthand door of Fig. 1; Fig. 4 is an elevational view similar to Fig. 3 but showing the type of lock which has previously been illustrated on the doors more 15 particularly shown in Fig. 2; Fig. 5 is a part sectional, part side elevational view of a door lock adapted to be used in place of the master lock of Fig. 3 in the system illustrated in Figs. 1 and 2; Fig. 6 is a part sectional, part side elevational 20 view of the lock illustrated in Fig. 5 with the parts thereof so arranged that it is in the so-called locked position; Fig. 7 is a fragmentary perspective view of the apparatus positioned in the stile between the two locks illustrated in Fig. 30 1; Fig. 8 is a fragmentary perspective view of the apparatus located in the stile between the locks illustrated in Fig. 2; Fig. 9 is a side elevational view of a slightly different form of master lock 35 which may be substituted in place of either of the locks of Figs. 3 and 5 in the system illustrated in Figs. 1 and 2 or employed in conjunction with a system having a different type of remote lock such as is illustrated in Fig. 12; Fig. 40 10 is a transverse sectional view of a portion of the lock illustrated in Fig. 6 taken on a plane substantially indicated by the line 10—10; Fig. 11 is a perspective view of the dog shown in the lower lefthand corner of Fig. 6; Fig. 12 is a so-called remote lock which may be substituted in 45 place of the remote lock of Fig. 4 in the system illustrated in Figs. 1 and 2 or employed in a similar system in conjunction with a master lock such as is illustrated in Fig. 9; Fig. 13 is an end 50 elevational view of a bolt-actuating handle such 55

as may be employed in conjunction with the master lock illustrated in Fig. 9; Fig. 14 is a transverse sectional view partially in elevation of the handle illustrated in Fig. 13 taken on a plane substantially indicated by the line 14-14; and Fig. 15 is a transverse sectional view of the handle as illustrated in Fig. 14 taken on a plane substantially indicated by the line 15-15.

Referring now more specifically to the drawings and more especially to Figs. 1 and 2, it will be noted that the coincidental locking system here illustrated and constructed in accordance with the principles of my invention is shown associated with four doors 1, 2, 3, and 4 which may be the paired doors on opposite sides of a closed vehicle body. As previously indicated, it is to be understood that while the ensuing description of my invention refers to the same as being applied to the four doors of a closed vehicle body, nevertheless, such system is applicable to be used in conjunction with a vehicle body having only two doors and may also be utilized to lock other portions of the vehicle body such as the cover for the engine compartment and the cover for a luggage compartment etc.

During the course of the ensuing description the door 1, which it will be assumed is the right-hand front door of the vehicle, will be referred to, for convenience, as the master door, i. e., the door upon which occurs the station from which the several remaining doors or closures of the vehicle are locked.

Before going on to a detailed description of the system as illustrated in Figs. 1 and 2, it is believed advisable to first describe the construction of the locks which form the component parts of such system.

Referring now, therefore, more particularly to Fig. 3, it will be noted that the so-called master lock here illustrated utilizes the usual base plate generally indicated at 5, which is provided with the usual laterally extending flange 6 through which the bolt 7 of the lock projects. The terminal 8 of the bolt 7 is normally maintained in engagement with the stile or jamb of the door by means of a suitable spring such as 9. The usual means will, of course, be provided for maintaining the bolt 7 in freely slidable position in the lock, i. e., suitable supports for the bolt will be provided, which, however, are so well known to those familiar with the art that for purposes of simplicity of illustration they have not been included in the drawings.

Extending through the plate 5 of the lock is a handle stem shown in cross section at 10, which stem may extend, outwardly through the door, a terminal provided with a hand-grip to facilitate turning of the stem 10 in the lock. Mounted on the stem 10 is a roll-back 11 which, being provided with a square opening for the reception of the stem 10, is turned when the handle is rotated. As most clearly illustrated in Fig. 1, the bolt 7 may have a link 12 connected thereto and to which the crank 13 from a second handle, usually on the inside of the door, is connected. Ordinarily, therefore, the bolt 7 may, through the apparatus presently to be described, be moved slidably into and out of engagement with the stile or jamb by a rotation of either the outside handle, the stem of which is shown at 10, or the inside handle, the crank lever of which is shown at 13.

Pivots supported on the bolt 7 by means of a pin 14 is a hook-shaped link, generally indicated at 15, one end 16 of which is normally in

engagement with the roll-back 11. The link 15 is maintained in engagement with the roll-back by means of the spring 17 which, at one end, is secured to the arm 18 of the link 15 and at its other end, is secured to a pin 19.

Pivots supported on the plate 5 by means of the pin 20 is a lever, generally indicated at 21, which, at its lower end, as viewed in Fig. 3, is provided with a laterally projecting flange 22 adapted to engage the arm 18 of the keeper 15. The pin 19 to which one end of the spring 17 is secured is carried by the lever 21 and such pin may have secured thereto one end of a spring 23 which, at its opposite end, is anchored by means of a pin 24 on the plate 5.

Slidably mounted in suitable guideways not shown on the plate 5 is a pin or bar 25 which, at its rear end 26, is provided with a lateral projection directed towards the plate 5 so that the upper end of the arm 21 lying between the pin 20 25 and the plate 5 may engage such projection 26 when the lever 21 is urged in a clockwise direction under the influence of the spring 17.

Pivots supported on the plate 5 by means of a pin 28 is an angle-shaped arm generally indicated at 29 and which has a depending leg 30 projecting to a point adjacent the axis of the roll-back 11. The member 29 is provided with a projecting ear 31 which, when the pin 25 is moved to the left into the dotted line position generally indicated at 32, will drop into the recess 33 on the pin 25 and maintain the same in the dotted line position until released in the manner hereinafter more fully explained.

As previously indicated, the lower end of the leg 30 of member 29 extends to a point adjacent the shaft 10 of the handle. The shaft 10 may be of the usual form such as is illustrated in Fig. 19 of my co-pending application Ser. No. 655,180, i. e., the shaft 10 of the handle has a transversely extending pin which is moved transversely with respect to such shaft as the key is rotated in the handle. The pin is illustrated at 34 with the lower end of the leg 30 resting thereon in the position normally referred to as the unlocked position. When the key is turned in the handle so that the pin 34 descends permitting the leg 30 to descend likewise under the influence of the spring 35, the ear 31 on such leg may, thereafter, drop into the recess 33 after, of course, the pin 25 has been moved to the left by a counterclockwise rotation of the roll-back 11. Movement of the pin 25 to the left, upon counterclockwise rotation of the roll-back 11, is made possible by the upper end of the roll-back engaging a stud 36 carried by the pin 25. The length of the vertically projecting portion of the roll-back 11, as well as the relative position of the stud 36 on the bar or pin 25, is such that when the roll-back has been rotated in a counterclockwise direction for a distance sufficient to permit the ear 31 to drop into the recess 33 and hold the pin 25, then the upper end of the roll-back will pass under the stud 36.

The so-called remote lock illustrated in the system shown in Figs. 1 and 2 is shown drawn to an enlarged scale in Fig. 4. The lock illustrated in Fig. 4 includes the usual base plate 37 slidably supporting a bolt 38 which is normally urged to the left and into engagement with the stile or jamb by means of the spring 39. The shaft 40 of the handle associated with this lock has a roll-back 41 mounted thereon which is substantially circular in form and provided with notches 42 and 43. Pivots supported on

the plate 37 by means of a stud 44 is a lever 45. Pivots mounted on the lever 45 by means of a stud 46 is a second lever 47. The lefthand end of the lever 47 is normally maintained in engagement with the roll-back 41 in the notch 42 by means of a spring 48 which urges the lever 47 for rotation in a counterclockwise direction about the axis of the stud 46. The lower end of the lever 45 is arranged to engage a projection 49 on the bolt 38.

Slidably mounted in suitable guides 50 on the base plate 37 is a pin 51, at its lefthand end projecting through the laterally extending flange of the base plate and at its righthand end bearing against the vertically disposed leg 52 of the lever 47.

From the foregoing description of the master lock and the lock associated with the remote doors, it will be apparent that when it is sought to rock the several doors on the vehicle, this may be accomplished by a movement out of the lock, i. e., to the left, of the pin 25 associated with the master lock and a movement into the remote locks of the pins 51 associated therewith. The center posts of the automobile body between the doors 1 and 2 on one side and between the doors 3 and 4 on the other are provided with horizontal slots which receive and pass freely the projecting ends of the pins 25 and 51 so that they do not interfere with the opening and closing of the doors. This construction is similar to that described in my above-mentioned pending application Ser. No. 655,180. The mechanism by which the pins 51 of the remote locks may be forced into the locks as the pin 25 is moved out of the master lock will now be described.

In the stile between doors 1 and 2 is positioned apparatus clearly illustrated in perspective in Fig. 7.

Mounted on the stile are two pairs of angle brackets 53, each pair supporting therebetween a pin 54. Oscillatably supported upon the pins 54 are tablets 55. Slidably supported between the paired angle brackets 53 is a bar 56 which, at its opposite ends, is provided with lateral extensions 57 which engage the tablets 55. Pivots mounted on the stile by means of a pin 58 is a bellcrank 59. One leg 60 of the bellcrank engages the bar 56 at 57 and said bar engages the tablet 55 adjacent the pin 25 and to its other leg 61 such bellcrank has secured a wire or cable 62 by means of a pin 63. The pin 63 may project into a guiding slot 64 therefor formed in the stile post. A sleeve 66, a short portion of which is shown in Fig. 7 may be provided, through which the cable 62 is guided.

The apparatus positioned in the stile post between the two remote locks illustrated in Fig. 2 is most clearly illustrated in perspective in Fig. 8. Two pairs of angle brackets 67 carried by the stile post, respectively support pins 68 upon which are oscillatably mounted tablets 69. The stile post also carries two oppositely disposed bellcranks 70 and 71, the lower leg of each respectively engaging one of the tablets 69 and to the other legs of which there are secured the wires 72. The wires 72 are joined to the cable 62 which, it will be noted, is at its opposite end connected to operating mechanism in the stile post between the locks on the other side of the car. The cable 62 may pass from one side of the car to the other, either upwardly and around in the roof structure, or downwardly and around in the seat structure. As illustrated in Figs. 1

and 2, the wires are shown passing downwardly and around through the seat structure. The means for guiding the cable or wire 62 may either include a plurality of guiding sleeves, such as 66 and 74, or a single continuous guiding tube 5 may be provided for the wire from one stile post to the other.

The operation of the system illustrated in Figs. 1 and 2 may now be briefly described in the light of the foregoing description of the 10 operation of its component parts. The parts as illustrated in Figs. 1 and 2 are in the position which they would occupy when the doors are unlocked.

Assuming now, therefore, that it is desired 15 to lock the four doors of the vehicle, the handle associated with the master lock on door 1 will first be rotated in a counterclockwise direction as viewed in Fig. 1. Such rotation of the handle will cause a counterclockwise rotation of the 20 roll-back 41, moving the pin 25 to the left into the dotted-line position illustrated at 32 in Fig. 3. It is assumed, of course, that the key has first been rotated in the handle of the lock of the master door so as to move the pin 34 downwardly so that after the pin 25 has been moved to the left, the lever 29 may rotate in a counterclockwise direction under the influence of a spring 35 sufficiently to cause the ear 31 carried thereby to move into the recess 33 and 25 maintain the pin 25 in the dotted line position. Movement of the pin 25 towards the left, as viewed in Figs. 1 and 3, will cause a movement to the left of the bar 56, most clearly illustrated in Fig. 7. The movement of the bar 56 to the left will cause a movement to the left of the pin 51 projecting out of the remote lock 30 positioned on door 2. Movement of the pin 51 to the left or into the remote lock on door 2 corresponds to a movement to the right of the 35 pin 51 as illustrated in Fig. 4.

Movement of the pin 51 to the right, as illustrated in Fig. 4, will result in a clockwise rotation of the lever 47 into the dotted line position illustrated in Fig. 4, whereupon the lefthand end of such lever will be lifted out of engagement with the roll-back 41. With the lever 47 lifted out of engagement with the roll-back 41, then such roll-back and the handle associated therewith may be rotated without a withdrawal 40 of the latch bolt 38.

Movement of the pin 25 of the master door to the left, as illustrated in Fig. 7, results in a clockwise rotation of the bellcrank 39 and a consequent tensioning of the wire or cable 62. Tensioning of the wire or cable 62 will result in a downward movement of the inner ends of the bellcranks 10 and 11, as illustrated in Fig. 8; such movement will result in a spreading action of the pins 51 of the remote locks extending into the 55 stile post of this side of the car, i. e., the pins on these remote locks will be moved into such locks with a consequent freeing of the roll-backs in the manner described in connection with the explanation of Fig. 4.

Movement of the pin 25 to the left into the dotted line position illustrated at Fig. 3, in the manner above explained, will cause such pin acting through the projection 26 engaging the lever 21 to cause such lever to rotate in a counterclockwise direction about its supporting pin 20. Movement of the lever 21 in a counterclockwise direction causes the lever or link 15 to be rotated in a clockwise direction about its supporting pin 14 into the dotted line position illustrated in Fig. 75

3. The member 15 being thus moved into the dotted line position will swing out of the path of the roll-back 11 so that the handle on the master door and its associated roll-back may be rotated 5 freely without retracting the bolt 7 on such master door.

The procedure which has been just explained has resulted in a locking of all of the doors of the car by operably disconnecting the handles from 10 the bolts, i. e., no amount of turning of such handles will result in an actuation of the bolts.

Assuming now that it is desired to unlock the car:—The only thing required to be done is to rotate the key in the handle of the master door 15 so as to move the pin 34 upwardly into the position illustrated in Fig. 3. Such movement will cause a slight clockwise rotation of the lever 29 carrying the ear 31 out of the recess 33 so that the spring 17 and/or 23 may return the pin 25 20 and the levers 15 and 21 to the full line position illustrated in Fig. 3. When the parts are in this position, a clockwise rotation of the roll-back 11, as viewed in Fig. 3, will, due to the engagement therewith of the link 15 which is connected to the 25 bolt 7, cause a retracting movement, i. e., movement to the right of the bolt 7.

As soon as the pin 25 in the master door is returned to its full line position in Fig. 3, the springs 48 associated with the remote locks, return the 30 parts of such locks to the full line position as illustrated in Fig. 4, i. e., the lever 47 will be returned to engagement with the roll-back 41, so that when the handle associated with this door is moved in a clockwise direction, as illustrated in 35 Fig. 4, the lever 47 resting in a notch 42 of the roll-back will be moved to the right causing a counterclockwise rotation of the lever 45 about its supporting pin 44. The lower end of the lever 45 is, therefore, urged to the right retracting the 40 bolt 38 associated with the remote lock.

When the parts of the remote locks are in the dotted line position, as illustrated in Fig. 4, i. e., when the doors are locked by an operable disconnection of the handle from the bolt, the spring 43a resting in the notch or groove 43 in the roll-back will maintain the handle of the door from rotation due to jarring so that when the doors are unlocked in the manner just described, the lefthand end of the lever 47 may drop into proper 50 engagement with the notch 42 in the roll-back 41.

The above described apparatus is characterized by the fact that the locking of the doors is effected by operable disconnection of the handles from their associated bolts on the several doors. 55 When such apparatus is employed and the car is locked from the outside, it is, of course, possible for an occupant of the locked car to open a door and leave the car by merely rotating the inside handle on one of the doors. For instance, a clockwise rotation of the arm 18 associated with the inside handle of the lefthand front door (Fig. 2) will result in a retractive movement of the bolt associated with this door so that the door may be opened. After the occupant has left the 60 car in the manner described, the door may be slammed, whereupon the parts are restored to the locked position and the car again fully locked. Likewise a person within the car may, from a central station, lock all the doors. The crank 13 65 on the inside handle of door 1 (Fig. 1) extends upward beyond its connection with the link 12. Mounted on a stud adjacent the upper end of crank 13 is a bellcrank lever 201 with a lower arm engaging said crank 13. Mounted on a stud 70 adjacent the inner end of pin 25 is a bellcrank 75

lever 202 with a lower arm in contact with the end of said pin. A wire 203 connects the upper arms of said bellcranks. Before entering the car one may turn the key to the locking position, i. e., retract the pin 34 within the shaft 10, and after entering the car may lock all the doors by movement of the handle on door 1 (Fig. 1) in a direction, anticlockwise as shown in said drawing. Such rotation will, through the crank 13, the bellcranks 201 and 202 and the wire 203, shift the 10 pin 25 to the left, locking all the doors, just as was done by anti-clockwise rotation of the roll-back 11 and shaft 10 through the outside handle in the explanation hereinbefore given.

It will be noted that when a master lock of 15 the type illustrated in Fig. 3 is employed, the radial projection of that portion of the roll-back required to engage the pin 25 may be so long as to interfere with the complete rotation of the roll-back 11 when the doors are locked, i. e., 20 when the apparatus illustrated in Fig. 3 is locked, an unauthorized person seeking entry into the car might, by forcing the handle around in either direction, move the radial extension of the roll-back into engagement with the laterally extending flange 6 of the base plate or into engagement with the bolt 7 and if sufficient pressure were exerted, might cause a breaking of either the handle or some other part of the mechanism. The master lock illustrated in Figs. 5 and 6 is 30 designed to overcome this difficulty, i. e., when the master lock in Figs. 5 and 6 now to be described is locked, the handle may be freely rotated without doing any damage to any part of the mechanism.

The lock illustrated in Fig. 5 includes a base-plate 75 which has slidably supported thereon a bolt 76. A spring 77 urges the bolt into the stile or jam adjacent the lock and normally maintains the door in a latched condition. The 40 shaft of the handle for actuating this lock is illustrated in section at 71. Such shaft carries a transversely movable pin 78 similar, in certain respects, to the pin 20 illustrated as a part of the handle assembly in Fig. 19 of my co-pending application Ser. No. 655,180. In the construction 45 illustrated in Fig. 5, however, the pin is such that when the key in the handle is rotated to the locked position, such pin 78 will be positioned substantially entirely within the shaft 77, for the reason hereinafter more fully explained. The shaft 77 has a roll-back 79 secured thereto. The roll-back 79 is substantially circular in outline with a notched-out portion, generally indicated at 80, in Fig. 6. Slidably mounted on a 50 suitable bracket 81 carried by the plate 75 is a bar 82. The bar 82 is resiliently maintained on its supporting bracket by means of a U-shaped spring 82' which is carried by a stud 82a. The lefthand end of such bar is provided with a cam 60 surface 83' adapted to be engaged by the roll-back 79 at one end of the notch 80, upon clockwise rotation of the roll-back as viewed in Fig. 5. Positioned adjacent the righthand end of the 65 slidable bar 82 is a vertically disposed arm 83. The upper end 84 of such arm extends into a groove in the bolt 76 so that when such upper end 84 is moved to the right, it will carry the bolt 76 along therewith. The lower end of the member 83 carries a pin 85 which extends 70 through and is slidable in an opening 86 in the plate 75. The pin 85 carries a small bracket 87 to which there is secured a spring 88 and the other end of such spring is anchored at 89 on the plate 75.

Pivots supported by means of a pin 81 on the plate 75 is a bellcrank 92. A spring 93 secured at 94 to the bellcrank 92 and at its other end 95 to the plate 75 urges the bellcrank 92 for 6 rotation in a counterclockwise direction. The lefthand end of the bellcrank 92 is arranged to engage a collar 96 mounted on the pin 85.

Slidably supported on the plate 75 by means of brackets such as 97 is a Z-shaped bar 98. The 10 righthand end of such bar 98 carries a stud 99 which projects into a slot 100 formed in one leg of the bellcrank 92. The lefthand leg of the Z-bar 98 extends out of the lock as at 26a and this projection corresponds to the pin 25 of the master lock illustrated in Fig. 3.

The Z-bar 98 is at 101 provided with a shoulder adapted to be engaged by a cam member 102. The cam member 102 is supported for rotation by means of a stud 103 carried by the plate 75. The 20 cam member 102 has a projection generally indicated at 103' which is adapted to be engaged by the roll-back 78 at the righthand end of the notch 80, so that when the roll-back 78 is rotated in a counterclockwise direction from its 25 position, as illustrated in Fig. 5, the cam member 102 will be rotated in a clockwise direction and by engagement with the shoulder 101, force the Z-bar 98 towards the left.

Pivots mounted by means of a pin 104 on 30 the plate 75 is a dog 105, the form of which is most clearly illustrated in Fig. 11.

The dog 105 carries a lateral projection 106 adapted to be engaged by the pin 78 of the handle shaft 77. The dog 105 also carries an ear 107 35 adapted to enter a notch 108 in the Z-bar 98 after such bar has been moved to the left upon counterclockwise rotation, as above described, of the roll-back 79. A spring 109 anchored to the plate 75 by the stud 110 and extending over the 40 pin 104 and engaging the dog 105 under the shoulder 111 thereof resiliently urges the dog upwardly into engagement with the Z-bar so that when such bar is moved to the left, the projection 107 thereon may move into the notch 108 on the 45 bar.

The operation of the master lock illustrated in Figs. 5 and 6 may be briefly described as follows:—The position of the parts, as illustrated in Fig. 5, is the position which they occupy when the door is unlocked, i. e., when rotation of the roll-back 50 79 is effective to retract the bolt 76 and the position of the parts, as illustrated in Fig. 6, is that which they occupy when the door is locked, i. e., when rotation of the roll-back 79 may occur 55 freely without engagement with any of the parts of the lock and consequently, without a withdrawal of the bolt 76.

When the parts are in the position illustrated in Fig. 5, i. e., the unlocked position, the bolt 60 may be retracted by the rotation in a clockwise direction of the roll-back 79. The roll-back 79, when so rotated, moves the bar 82 to the right against the vertically disposed bar 83. In the unlocked position, the bellcrank 92 is in engagement with the pin 85 upon which the lower end 65 of the vertical bar 83 is mounted. With the bellcrank 92 in the position illustrated in Fig. 5, movement to the right of the bar 82 will cause a clockwise rotation of the bar 83 about the axis of the pin 85. The rotation of the roll-back 79 in a clockwise direction, in order to effect a 70 withdrawal of the latch bolt 76, has no effect on the cam 102 and the mechanism associated therewith for the reason that the bolt is completely retracted before the lefthand end of the notch 75

80 in the roll-back reaches the upper lefthand end of the cam 102.

Assuming now that it is desired to lock the master door and to coincidentally lock all of the other doors of the vehicle body associated with 5 the master door: The key in the handle of the lock will first be rotated to move the pin 78 into the shaft 77 of the handle, permitting the dog 105 to be rotated in a clockwise direction under the influence of a spring 109 into engagement 10 with the Z-bar 98. The handle of the lock and consequently the roll-back 79 attached thereto is then rotated in a counterclockwise direction as viewed in Fig. 6. Such counterclockwise rotation of the roll-back will, in the manner previously 15 explained, cause a clockwise rotation of the cam member 102. The cam member 102 bearing against the shoulder 101 on the Z-bar will cause such bar to be moved to the left for a distance sufficient to bring the projection 107 on the dog 20 and the notch 108 on the bar into register. The spring 109 then moves the dog into the notch 108 and the Z-bar is held in the position illustrated in Fig. 6, i. e., with its terminal 82a projecting out of the lock for a distance greater than 25 when the parts are in the unlocked position, as illustrated in Fig. 5.

Movement of the Z-bar 98 to the left in the manner explained causes a clockwise rotation of the bellcrank 92 about the axis of its supporting 30 pin 91. Such clockwise rotation of the bellcrank moves the lefthand end thereof out of engagement with the pin 85 or more particularly, the collar 96 mounted thereon.

When the parts have been moved into the position just described, the handle of the lock and the roll-back 79 associated therewith may be rotated in either direction to any extent without retracting the bolt 76 of the master lock or in any way disturbing the setting of the Z-bar 98 40 which maintains the remote locks in the latched condition. Should the roll-back 79 be rotated in a counterclockwise direction it will merely displace the bar 82 upwardly against the spring 82' but without in any way moving the bolt 76 or 45 the bar 98. Should the roll-back 79 be rotated in a clockwise direction, the bar 82 will be moved to the right but since the bellcrank 92 has been disengaged from the pin 85 upon which the lower end of the bolt-actuating bar 83 is mounted, the 50 lower end of such bar 83 will move to the right by a sliding of the pin 85 in the opening 86. The lower end of the bar 83 will move to the right rather than the upper end, due to the fact that the spring 11' urging the bolt 76 to the left, is 55 much stronger than the spring 88 which urges the lower end of the bar 83 to the left.

The roll-back 79, if further rotated in a clockwise direction, will ultimately move the bar 82 to the right for a distance sufficient to permit the 60 roll-back to be rotated for a complete revolution.

It will be noted that the master lock illustrated in Figs. 5 and 6 is characterized particularly by the provision and arrangement of parts whereby, when the lock is locked, the handle and the roll-back associated therewith, may be rotated in either direction without withdrawing the bolt 76 or in any way disturbing the setting of the bar 98 upon which the locking of the remote doors depends. The only thing which remains to be 70 done when it is desired to unlock the car is to rotate the key in the handle moving the pin 78 into engagement with the dog 105, depressing the same and permitting the springs 88 and 93 to return the parts to the position illustrated in 75

Fig. 5. As soon as the bar 98 is moved to the right, tension on the wire or cable 62 connecting the master lock with the other locks in the series is relieved, thereby permitting the springs 48 associated with the remote locks to restore the parts thereof into an unlocked position.

The locks and the system in which the same are employed, as above described, are all characterized by the fact that the locking of the several doors is accomplished by disconnecting the several handles from their respective door-latching bolts. When such arrangement is employed, the bolts may, of course, be retracted by an actuation of the inside handle moving the link 12 and the arm 13. It is also possible, of course, that in certain types of installation, unauthorized entry of the car may be achieved by the insertion of a thin instrument between the door and its associated jamb or stile to force back into retracted position the bolt which maintains the door closed. Ordinarily, there is no difficulty on this account, due to the fact that the doors overlie the stile post to a certain extent, thereby obviating the possibility of a retraction of the bolt as just described. In certain types of construction, however, it may be desirable to positively lock or dog the several bolts associated with the several doors, so that when the car is locked the several doors may not be opened except by a proper manipulation of the master lock.

A master lock in which the bolt is so positively dogged as just described is illustrated in Fig. 9 and the handle associated with such lock is shown in Figs. 13 to 15. A remote lock which may be associated with a master lock of the character illustrated in Fig. 9 is shown in Fig. 12.

Referring now more particularly to Fig. 9, it will be noted that the lock here shown comprises a base plate 112 upon which there is slidably mounted a bolt structure generally indicated at 113. The bolt structure in this lock is somewhat more expensive than the simple slide bolts variously illustrated in the previously described figures. The bolt structure 113 includes a pressed steel body 114 to which there is attached a cam-faced bolt member 115 adapted to engage the stile or jamb of the door to maintain the same in closed position. A shouldered rivet 116 carried by the plate 112 and passing through an elongated opening 117 in the bolt plate 114 slidably supports the same at its righthand end. The shaft 118 of the bolt-actuating handle of the lock carries a roll-back 119. The roll-back 119 bears against a laterally extending flange 120 on the bolt plate 113 and extends into a notch in a slide bar 121. The slide bar 121 is mounted on a stud 122 and is normally maintained in the position illustrated in Fig. 9 by means of a spring 123.

As previously indicated, the form of handle employed in conjunction with the master lock illustrated in Fig. 9 is shown in Figs. 13 to 15. Such handle, generally indicated at 123, comprises the stem portion 118 in the outer body portion 124. The outer body portion 124 and the stem portion 118 are rigidly connected together and an escutcheon 125 is rotatably mounted on the outer body portion. A coiled spring 126 is mounted between cup members 127 and 128 respectively secured to the handle and bearing against the inner face of the escutcheon. The function of this spring is to resiliently maintain the outer body portion of the handle in snug engagement with the escutcheon.

The outer body portion of the handle is pro-

vided with a key-controlled barrel 129 which, at its inner end, is provided with an eccentric pin 130 which engages a dog 131 slidably mounted in a transverse groove in the handle. As the barrel is rotated by means of the key 132, the dog 131 is moved into a recess 133 in the escutcheon, the escutcheon being secured to the door by some suitable means such as bolts, screws, or the like passing through spaced openings 134 therein. The handle will be held against rotation when the dog is moved into the recess 133, as illustrated in Fig. 15.

The normal position of the handle when the master door is unlocked is as illustrated in dotted lines in Fig. 13. When the handle is rotated in a clockwise direction from such dotted line position, it will result in a clockwise rotation of the roll-back 119 and a consequent movement to the right of the bolt 113, so that the door may be opened. If, however, the handle is rotated in a counter-clockwise direction from the dotted line position illustrated in Fig. 13, to the full line position illustrated in such figure, the roll-back 119 likewise rotating in a counter-clockwise direction, will move the slide 121 to the left, i. e., out of the lock.

It will be noted that the slide bar 121 corresponds to the members 25 and 25a of the previously described master locks, so that the master lock illustrated in Fig. 9 may be substituted for either of the previously described master locks in the system illustrated in Figs. 1 and 2.

As previously indicated, it may be desirable to dog the bolts on the several remote doors instead of merely operably disconnecting their actuating handles therefrom. A remote lock structure functioning in this manner is illustrated in Fig. 12.

The lock illustrated in Fig. 12 comprises a base plate 135 upon which is slidably mounted a bolt assembly 136, similar in certain respects to the bolt assembly 113 of the lock illustrated in Fig. 9. A shouldered rivet 137 carried by the plate 135 and passing through an elongated opening 138 in the bolt plate cooperating with flanges 139 on the base plate 135 slidably support the bolt assembly on the base plate. The cam-faced bolt member 140 forming a part of the bolt assembly and passing through an opening provided therefor in a laterally projecting flange 141 on the base plate 135 additionally slidably supports the bolt assembly on the base plate. A spring 142 urges the bolt assembly 136 to the left, i. e., tends to maintain the several parts of the lock in the position illustrated in Fig. 12.

The shaft 143 of the handle carries a roll-back 144 adapted to engage a flange 145 on the bolt plate so that when the roll-back is rotated in a clockwise direction, the bolt assembly may be moved to the right and the cam-faced bolt member 140 retracted from the stile or jamb.

Slidably supported on the base plate by means of a pin 146 and a bracket 147 is a bar 148, which corresponds to the members 51 of the previously described remote locks.

Pivotedly supported on the base plate 135 by means of a stud 149 is a rocker arm 150. A spring 151 anchored at 152 to the base plate and at 153 in engagement with the rocker arm forces such arm into engagement with the bar 148 and resiliently urges such bar to the left.

Pivotedly mounted on a stud 154 on the base plate is a dog 155. The dog 155 carries a stud 156 which extends into a slot formed on the lower face of the bar 148. The bolt plate carries a pin

157 which extends into the plane defined by the pivotally supported dog 155.

5 The parts of the lock shown in Fig. 12 are arranged in the position which they occupy when the lock is in unlocked condition. Clockwise rotation of the handle of the lock and the roll-back 144 associated therewith results in a retractive movement of the bolt assembly.

10 Assuming now, however, that the master lock 10 and its associated train of apparatus has been energized to force the bar 148 to the right, i. e., to a locking position: Movement of the bar 148 to the right will result in a clockwise rotation of the dog 155 about the axis of the stud 154, so that the 15 dog is moved into the dotted line position illustrated in Fig. 12. When the dog occupies the dotted line position illustrated in Fig. 12, it lies in the path of movement of the stud 157, when an attempt is made to retract the bolt, i. e., move the 20 bolt assembly 136 to the right.

25 The bolt in the lock illustrated in Fig. 12 is, therefore, positively dogged and may not be retracted except by a breaking of some part of the lock until the bar 148 is restored to the full line position illustrated in Fig. 12, thereby permitting the dog 155 to move out of the path of the stud 157.

30 From the foregoing description it is believed that the construction and operation of the several components of my invention may be fully understood without a further detailed explanation or description.

35 It should be noted that while several different forms of master locks, as well as several different forms of remote locks, have been illustrated and described, nevertheless, any particular form of either type lock may be used in the general system illustrated and described along with any other form of described lock in the system.

40 Other modes of applying the principle of my invention may be employed instead of the one explained, change being made as regards the mechanism herein disclosed, provided the means stated by any of the following claims or the 45 equivalent of such stated means be employed.

I therefore particularly point out and distinctly claim as my invention:

1. In a coincidental locking system for a plurality of doors, the combination of a latch bolt 50 associated with each of said doors, both actuating means including a handle on each door normally adapted upon rotation of said handle to move its associated bolt, and means functionally responsive to rotation of one of said handles for operatively disconnecting another of said handles from its associated bolt.

2. In a coincidental locking system for a plurality of doors, the combination of a latch bolt 60 associated with each of said doors, bolt actuating means including a handle on each door normally adapted upon rotation of said handle to move its associated bolt, and means functionally responsive to rotation of one of said handles in a direction counter to its bolt retracting movement for operatively disconnecting a plurality of said handles from their associated bolts.

3. In a coincidental locking system for a plurality of doors, the combination of a latch bolt 70 associated with each of such doors, bolt actuating means including a handle on each door normally adapted upon rotation of said handle to move its associated bolt, means functionally responsive to rotation of one of said handles for simultaneously operably disconnecting all of said 75 handles from their associated bolts, and key-con-

trolled means for maintaining said handles in said disconnected relation.

4. In a coincidental locking system for a plurality of doors, the combination of a latch bolt 5 associated with each of such doors, bolt actuating means including a handle on each door normally adapted upon rotation of said handle to move its associated bolt, means functionally responsive to rotation of one of said handles in a direction counter to its bolt retracting movement 10 for simultaneously operably disconnecting all of said handles from their associated bolts, and key-controlled means for controlling said last named means.

5. In a coincidental locking system for a plurality of doors, the combination of a latch bolt 15 associated with each of said doors, bolt actuating means including a handle on each door, a roll-back connected to each handle and means operably connecting each such roll-back with its 20 associated bolt, and means functionally responsive to rotation of one of said handles and its connected roll-back in a direction counter to normal bolt retracting movement for simultaneously operably disconnecting all of said roll-backs 25 from their associated bolts.

6. In a coincidental locking system for a plurality of doors, the combination of a latch bolt 30 associated with each of said doors, bolt actuating means including a handle on each door, a roll-back connected to each handle and means operably connecting each such roll-back with its associated bolt, means functionally responsive to rotation of one of said handles and its connected roll-back in a direction counter to normal bolt 35 retracting movement for simultaneously operably disconnecting all of said roll-backs from their associated bolts, and key-controlled means for controlling said last named means.

7. In a coincidental locking system for a plurality of doors, the combination of a latch bolt 40 assembly associated with each of said doors, bolt actuating means including a handle assembly on each door and a linkage operably connecting said handle assembly with said latch bolt assembly, 45 said linkage secured to one of said assemblies and movable into and out of operable engagement with the other assembly, key-controlled means, and motion transmitting connections between said means and each of said linkages for holding the 50 said linkage on each of said doors out of operative engagement with the said other assembly on the respective doors.

8. In a coincidental locking system for a plurality of doors, the combination of a latch bolt 55 assembly associated with each of said doors, bolt actuating means including a handle assembly on each door and a linkage operably connecting said handle assembly with said latch bolt assembly, said linkage secured to one of said assemblies 60 and movable into and out of operable engagement with the other assembly, means functionally responsive to rotation of one of the handles on said doors for simultaneously moving the said linkage on each of said doors into and out of 65 engagement with the last named assembly on the respective doors, and key-controlled means for controlling said last named means.

9. In a coincidental locking system for a plurality of doors, the combination of a latch bolt 70 assembly associated with each of said doors, bolt actuating means including a handle assembly on each door and a linkage connected to said latch bolt assembly and movable into and out of engagement with said handle assembly whereby op- 75

- erable relation may be established between said assemblies, and means functionally responsive to movement of the handle on one of said doors for simultaneously moving the said linkage on each of 5 said doors into and out of engagement with its associated handle assembly.
10. In a coincidental locking system for a plurality of doors, the combination of a latch bolt associated with each of said doors, inside and outside bolt retracting handles on each of said doors, means operably connecting both handles on each of said doors with the latch bolt thereon, and means functionally responsive to rotation of one of said outside handles for simultaneously operatively disconnecting each of said outside handles from its associated bolt without disturbing the connection between such bolts and their associated inside handles.
11. In a coincidental locking system for a plurality of doors, the combination of a latch bolt associated with each of said doors, bolt actuating means including handle mechanism on each door, motion transmitting mechanism between each of said handle mechanisms and its associated bolt including separable parts adapted to be coupled and uncoupled and which when uncoupled render said handle mechanism ineffective to actuate said bolt, a slide bar on each door having an operative connection for actuating 30 said separable parts, and means operable from a single station for simultaneously actuating said slide bars.
12. In a coincidental locking system for a plurality of doors, the combination of a latch bolt associated with each of said doors, bolt actuating means including handle mechanism on each door, motion transmitting mechanism between each of said handle mechanisms and its associated bolt including separable parts adapted to be coupled 40 and uncoupled and which when uncoupled render said handle mechanism ineffective to actuate said bolt, a slide bar on each door extending to a point adjacent an edge of said door and having an operative connection for actuating said separable parts, motion transmitting mechanism between the slide bars of said doors whereby movement of a slide bar on one door is transmitted to another door, and means on one of said doors for actuating the slide bar thereof.
50. 13. In a door lock, bolt actuating means including a handle mechanism, motion transmitting mechanism between said handle mechanism and said bolt including separable parts adapted to be coupled and uncoupled and which when uncoupled render said handle mechanism ineffective to actuate said bolt, a slide bar extending to a point adjacent an edge of said door and having a connection with said motion transmitting mechanism for actuating said separable parts by motion applied to said slide bar.
55. 14. In a coincidental locking system for a plurality of doors, the combination of a latch bolt associated with each of said doors, a handle for each bolt, means normally operatively connecting each handle with its associated bolt, whereby each handle is operable to retract its bolt, means for disabling said last named means and for operatively disconnecting each handle from its associated bolt, a single controller, and motion transmitting connections between said controller and said disabling means and operable in disabling direction by actuation of said controller.
70. 15. In a coincidental locking system for a plurality of doors, the combination of a latch bolt assembly associated with each of said doors, a handle assembly associated with each of said bolts, releasable means operatively connecting each said latch bolt assembly with its associated handle assembly, the parts being so arranged that said handle assembly may completely revolve when released, and means operable from a single station for releasing a plurality of said handle assemblies from operative connection with their associated bolt assemblies.
10. 16. In a coincidental locking system for a plurality of doors, the combination of a latch bolt associated with each of said doors, handle means associated with each of said latch bolts, retracting means for each of said latch bolts having a part pivotally mounted on said latch bolt and normally operatively engaging said handle means, and a train consisting of interconnected movable elements for transmitting motion and operable from a single station for disengaging a plurality of said parts from their associated handle means.
15. 17. In a coincidental locking system for a plurality of doors, the combination of a latch bolt associated with each of said doors, handle means associated with each of said bolts, retracting means for retracting each of said bolts and normally operatively connecting each of said bolts with its associated handle means, and a train consisting of interconnected movable elements for transmitting motion and controllable from a single station for operatively disconnecting a plurality of said retracting means.
20. 18. In combination with an automobile vehicle having a door, a latch bolt on said door, and means for retracting said latch bolt, means for freeing said retracting means from operative connection with its bolt, said last named means including a part operable through a peripheral edge of said door, and a part engageable with said last named part when said door is closed whereby operation of said part will free said retracting means from operative connection with its bolt.
25. 19. In a coincidental locking system for a plurality of doors, the combination of a latch bolt associated with each of said doors, bolt actuating means on each door, a post adjacent an edge of each door, means for operably disconnecting each bolt actuating means from its associated bolt including a movable part on the adjacent post, and means operable from a single station operably associated with said movable part for actuating the same.
30. 20. In combination with an automobile vehicle having doors on opposite sides, a latch bolt for securing each of said doors, releasable means associated with at least one of said latch bolts for retracting the same, means for releasing said retracting means from association with said bolt, a train of movable parts for transmitting motion extending across said vehicle and operatively connected with said last named means, and said train of parts being arranged upon actuation from one side of said vehicle to release said retracting means from association with said bolt on a door on the other side of the vehicle.
35. 21. In combination with an automobile vehicle having doors side by side, a latch bolt associated with each of said doors, releasable means operatively associated with at least one of said latch bolts for retracting the same, means for releasing said retracting means from operative association with said latch bolt, a train of movable parts for transmitting motion from one door to

- the other and operatively connected with said last named means, and said train of parts being arranged upon actuation from one door to release said retracting means from association with 5 said bolt on the other door.
22. In combination with an automobile vehicle having a plurality of doors, a latch bolt associated with each of said doors, releasable means on at least one of said doors associated 10 with the latch bolt thereof for retracting the same, means for releasing said retracting means from association with said bolt, a lever movably mounted on another door, and mechanical means responsive to movement of said lever for releasing 15 said retracting means from association with said latch bolt on said one door.
23. In combination with an automobile vehicle having a swinging door having a free edge closing against a post of said vehicle, a latch bolt on said door, means for retracting said latch bolt including a roll-back adapted to operatively engage said bolt, means for freeing said roll-back from operative connection with its bolt, and said last named means including an operable 25 part in said free edge of said door.
24. In combination with a vehicle body having a plurality of doors, means for holding said doors in closed position, means operably associated with said holding means for operating the same, said operating means being disconnectable 30 from operable association with said holding means, and means including a train of movable parts for transmitting motion from a point remote from said doors and adapted upon actuation to disconnect said operable means from operable association with said holding means.
25. In combination with an automobile vehicle having a door, a latch bolt on said door, means operatively related to said bolt for retracting the same, and means for freeing said retracting 35 means from such operative relation with its bolt, said last named means including a part operably fastened to said door and operable through a peripheral edge of the door, whereby operation of said part will free the retracting means from its operative relation with its bolt.
26. In combination with a vehicle body hav-
- ing a door, releasable means for holding said door in closed position, control means operatively associated with said holding means for releasing the latter, and means for freeing said control means from operative connection with 5 said door holding means, said last named means including a part operable through a peripheral edge of said door and a part engageable with said last named part when said door is closed.
27. In combination with a vehicle body having a door, means for holding said door in closed position, means operatively associated with said holding means for operating the latter, said operating means being removable from operative association with said holding means, and means 10 for so removing said operating means from operative association with said holding means, said last named means including a train of operatively associated movable parts extending to a point remote from said door and there provided with 15 an actuator.
28. In combination with a vehicle body having a door, means for holding said door closed, means on said door adapted upon movement to release said holding means, and means to prevent the movement of said means on said door 20 from releasing said holding means including a train of operably associated movable parts extending to a point remote from said door and there provided with an actuator.
29. The combination with a vehicle body having a plurality of doors, means for holding at least one of said doors in closed position, means operably associated with said holding means for releasing said door, said operating means being disconnectable 25 from association with said holding means, means adapted upon actuation to disconnect said operable means from association with said holding means, said disconnecting means having associated therewith energy storing means for returning the parts to connected 30 relationship, and a train of operatively connected movable parts extending to a point remote from said door and there provided with an actuator for actuating said energy storing means.

EDWARD D. DALL.

Patent No. 2,135,967.

November 8, 1938.

EDWARD D. DALL.

It is hereby certified that error appears in the printed specification of the above numbered patent requiring correction as follows: Page 2, second column, line 10, for the word "keeper" read link; page 3, first column, line 20, for "rock" read lock; page 5, second column, line 24, for the reference numeral "52a" read 25a; and that the said Letters Patent should be read with this correction therein that the same may conform to the record of the case in the Patent Office.

Signed and sealed this 27th day of December, A. D. 1938.

Henry Van Arsdale

Acting Commissioner of Patents.

- the other and operatively connected with said last named means, and said train of parts being arranged upon actuation from one door to release said retracting means from association with 5 said bolt on the other door.
22. In combination with an automobile vehicle having a plurality of doors, a latch bolt associated with each of said doors, releasable means on at least one of said doors associated 10 with the latch bolt thereof for retracting the same, means for releasing said retracting means from association with said bolt, a lever movably mounted on another door, and mechanical means responsive to movement of said lever for releasing 15 said retracting means from association with said latch bolt on said one door.
23. In combination with an automobile vehicle having a swinging door having a free edge closing against a post of said vehicle, a latch bolt on said door, means for retracting said latch bolt including a roll-back adapted to operatively engage said bolt, means for freeing said roll-back from operative connection with its bolt, and said last named means including an operable 25 part in said free edge of said door.
24. In combination with a vehicle body having a plurality of doors, means for holding said doors in closed position, means operably associated with said holding means for operating the same, said operating means being disconnectable 30 from operable association with said holding means, and means including a train of movable parts for transmitting motion from a point remote from said doors and adapted upon actuation to disconnect said operable means from operable association with said holding means.
25. In combination with an automobile vehicle having a door, a latch bolt on said door, means operatively related to said bolt for retracting the same, and means for freeing said retracting 35 means from such operative relation with its bolt, said last named means including a part operably fastened to said door and operable through a peripheral edge of the door, whereby operation of said part will free the retracting means from its operative relation with its bolt.
26. In combination with a vehicle body hav-
- ing a door, releasable means for holding said door in closed position, control means operatively associated with said holding means for releasing the latter, and means for freeing said control means from operative connection with 5 said door holding means, said last named means including a part operable through a peripheral edge of said door and a part engageable with said last named part when said door is closed.
27. In combination with a vehicle body having a door, means for holding said door in closed position, means operatively associated with said holding means for operating the latter, said operating means being removable from operative association with said holding means, and means 10 for so removing said operating means from operative association with said holding means, said last named means including a train of operatively associated movable parts extending to a point remote from said door and there provided with 15 an actuator.
28. In combination with a vehicle body having a door, means for holding said door closed, means on said door adapted upon movement to release said holding means, and means to prevent the movement of said means on said door 20 from releasing said holding means including a train of operably associated movable parts extending to a point remote from said door and there provided with an actuator.
29. The combination with a vehicle body having a plurality of doors, means for holding at least one of said doors in closed position, means operably associated with said holding means for releasing said door, said operating means being disconnectable 25 from association with said holding means, means adapted upon actuation to disconnect said operable means from association with said holding means, said disconnecting means having associated therewith energy storing means for returning the parts to connected 30 relationship, and a train of operatively connected movable parts extending to a point remote from said door and there provided with an actuator for actuating said energy storing means.

EDWARD D. DALL.

Patent No. 2,135,967.

November 8, 1938.

EDWARD D. DALL.

It is hereby certified that error appears in the printed specification of the above numbered patent requiring correction as follows: Page 2, second column, line 10, for the word "keeper" read link; page 3, first column, line 20, for "rock" read lock; page 5, second column, line 24, for the reference numeral "52a" read 25a; and that the said Letters Patent should be read with this correction therein that the same may conform to the record of the case in the Patent Office.

Signed and sealed this 27th day of December, A. D. 1938.

Henry Van Arsdale
